DESIGN FOR A LINE GUIDE FOR A FISHING ROD

Arthur D. Sarkisian, New York, N. Y.

Application February 7, 1945, Serial No. 117,807

Term of patent 14 years

(Cl. D31—4)

To all whom it may concern:

Be it known that I, Arthur D. Sarkisian, a citizen of the United States, residing at 1150 Park Avenue, New York, New York, have invented a new, original, and ornamental Design for a Line Guide for a Fishing Rod, of which the following is a specification, reference being had to the accompanying drawing, forming part thereof.

In the drawing:

Fig. 1 is a side elevation of the line guide for a fishing rod showing my new design.

Fig. 2 is a top plan view of the same, and Fig. 3 is an end view thereof.

I claim:

The ornamental design for a line guide for a fishing rod, as shown.

ARTHUR D. SARKISIAN.
